[57] CLAIM

The ornamental design for a lid for jar, as shown and described.

DESCRIPTION

FIG. 1 is a front, top perspective view of a lid for jar showing our new design thereof;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a view similar to FIG. 1 of a second embodiment of the invention;

FIG. 8 is a top plan view thereof; and,

FIG. 9 is a side elevational view thereof, all other sides being identical.

The broken line showing of a jar is for illustrative purposes only and forms no part of the claimed design.
